UNITED STATES PATENT OFFICE.

ARTHUR H. QUARMBY, OF LANSING, MICHIGAN.

MUFFLER.

Application filed January 12, 1925. Serial No. 1,961.

The present invention relates to improved muffler constructions for the exhaust from internal combustion engines.

More particularly, the invention relates to an improved type of muffler for the exhaust of internal combustion engines and like uses in which the pressures and temperatures of the heated exhaust gases are reduced in the muffler to a point where they may be discharged into the atmosphere without the usual baffle arrangements relied upon in the ordinary and well known forms of such devices.

It is well known that the usual forms of baffle arrangements for muffling exhaust gases, or arrangements in which the flow of gases is reversed, develop back pressures which materially reduce the engine efficiency. Such prior constructions are also of a type which will not permit of ready access for cleaning.

In my improved muffler a whirling motion is induced in the heated gases which are rapidly cooled, and advanced through the muffler without abruptly arresting the advance thereof or reversing the direction of the flow. The whirling action creates a central zone of low pressure due to the centrifugal tendency of the rotating gases, which effects a material reduction in the back pressure on the engine and produces marked increases in efficiency of operation of engines when substituted for the present well known mufflers. Gases withdrawn from the central vortex are rapidly cooled and the pressures are progressively decreased in a manner to maintain rapid rotary movement of the exhausted gases and to maintain the central zone of low pressure. The lowered central pressure maintains the exhaust passages clear of free carbon particles and the whirling, rotary motion of the gases tends to maintain the free carbon which is deposited in ordinary baffle type mufflers, in suspension. In this manner a large percentage of the carbon which is deposited in the usual baffle type mufflers is withdrawn from the exhaust connections, passes through my improved muffler, and is discharged. Accordingly, an object of the invention is the provision of a muffler in which the back pressures due to muffling, and the free carbon deposit is reduced to a minimum.

Another object of the invention is to provide an improved muffler which may be rapidly and economically constructed.

Other objects of the invention are such as

may be attained by a utilization of the various combinations, subcombinations, and principles hereinafter more fully set forth, and as defined by the terms of the appended claims. 60

Referring to the drawings—

Fig. 1 is a sectional elevation showing a preferred form of the muffler construction.

Fig. 2 is a sectional view taken along line A—A of Fig. 1. 65

Fig. 3 is a sectional view taken along line B—B of Fig. 1.

Fig. 4 is a perspective view of the muffler with parts separated to show the construction. 70

The muffler comprises a central tube 1 which is adapted to be secured at one end to the usual exhaust pipe of an internal combustion engine in any well known manner, and which extends through end plate 2 of 75 barrel 3. Tube 1 is secured to plate 2 in any well known manner as by soldering, welding or the like, and has formed therein gas outlet slots 4 extending longitudinally in barrel 3. Communicating tangentially with slots 4 are 80 relatively, thin or constricted spirally shaped or curved veins or passages 5 formed of sheet metal which terminate in relatively large tubes or chambers 6. Tube 1 terminates in an end wall 7, flush with the end surface of 85 flange 8 formed on barrel 3, and secured between flange 8 and flange 9 of a discharge chamber 10 is a separating or dividing plate 11, against which the end 7 of tube 1 may abut. Formed integrally and communicat- 90 ing with tubes 6 are extensions or tubes 12. Tubes 12 pass through holes in plate 11 and are adapted to abut against end 13 of chamber 10 when the parts are assembled. Each tube 12 has formed therein diametrically op- 95 posite slots 14, from which the gases are discharged into chamber 10. To prevent the escape of gases from, or ingress of air to chamber 10 where tubes 12 pass through plate 11, suitable collars 15 may be formed 100 on tubes 6. Gases from the interior of chamber 10 pass outward to the atmosphere through discharge passage 16. To provide a suitable circulation of cooling air in barrel 3 and around the tubes 1 and 5 and veins 6, 105 air inlet openings 17 are provided in plate 2, and air outlet openings 18 are provided in barrel 3 near flange 8.

Operation.

110

In operation the engine exhaust is discharged into tube 1. The heated gases under

pressure then pass tangentially out through slots 4, and veins 5, and are discharged tangentially into tubes 6. The manner of withdrawing gases from tube 1 through slots 4 sets up a circular motion of gases and creates a vortex with lowered central pressures, and the manner of discharging into tubes 6 sets up a turbulent rotary action of gases in these tubes. The gases discharged into tubes 6 expand and pass forward into extensions 12. Due to the turbulence and whirling action of the gases created in tube 1, veins 5 and tubes 6, and the comparatively large area of metal surface over which the gases pass and with which they contact, an exceptionally high rate of heat transfer to the metal walls is attained. These metal surfaces are rapidly cooled by air entering through openings 17 in end plate 2 and passing out of barrel 3 through openings 18. The gases are cooled in this way at a very rapid rate and the pressures rapidly decrease as the gases pass outward through the veins 5 from tube 1 maintaining a continued high velocity flow of gases outward from the central action or vortex. In tubes 6 the gases expand and are further cooled, and pass through tubes 12 and slots 14 into the discharge chamber 10. The manner of discharge into chamber 10 through slots 14 creates a further turbulent action or agitation of the gases, permits expansion, and causes further cooling and reduction of pressures to the point where the gases will discharge into the atmosphere through passage 16 in properly muffled condition.

It will be noted that the gases are given a whirling motion and maintained in turbulent or agitated condition, while the action of the gases withdraws a substantial portion of the carbon ordinarily deposited in the engine, exhaust connections and muffler, by the suction effect by the freedom from direct obstructions to the flow of gases, and by the turbulent action of the gases which tends to maintain solid particles in suspension so that they are discharged with the gases. Because of the freedom baffles the structure readily lends itself to cleaning. By removing the muffler from the engine, tube 1 may be brushed clean; by removing chamber 10, tubes 12 and 6 may be brushed clean, and by removing plate 11, the interior of chamber 3 may be cleaned.

It will be understood that many variations of the disclosed structure may be made by those skilled in the art, all within the scope of the present invention as defined by the terms of the appended claims.

Accordingly, having described one preferred embodiment of my invention, what is desired to be secured by Letters Patent and claimed as new is:

1. A muffler for internal combustion engines, comprising a plurality of substantially parallel tubular sections arranged around a

central section designed to receive the engine exhaust gases, and means to induce a whirling motion in said tubular and central sections.

2. A muffler for internal combustion engines, comprising a plurality of substantially parallel tubular sections arranged around a central section designed to receive the engine exhaust gases, and passages between said sections arranged tangentially to said tubular sections whereby a whirling motion is set up in said sections. 70

3. A muffler for internal combustion engines comprising a plurality of substantially parallel tubular sections arranged around a central substantially tubular, gas receiving section, and passages between said sections, said passages being tangentially arranged with reference to said tubular and central sections whereby a whirling motion is set up in 80 said sections. 85

4. A muffler for an internal combustion engine comprising a central section into which the engine exhaust gases are discharged, a plurality of outlets formed in the wall of said section, said outlets being relatively narrow in width and of a substantial length compared to the length of said section, a plurality of enlarged sections arranged around said central section, and conduits conforming 90 substantially in cross section to said outlets connecting said central section to said enlarged sections. 95

5. The combination defined in claim 4 in which the conduits there specified are arranged to receive the gases from the central section in directions substantially normal to lines drawn from the longitudinal axis of said section to said outlet. 100

6. The combination defined in claim 4 in 105 which the conduits are arranged to discharge into said enlarged sections in directions that are substantially normal to lines drawn from the longitudinal axes of the enlarged sections to the points of discharge into said sections. 110

7. The combination defined in claim 4 in which the conduits are curved between their ends, and discharge into said enlarged sections in directions that are substantially normal to lines drawn from the longitudinal axes of the enlarged sections to the points of discharge into said sections. 115

8. The combination as set forth in claim 4 together with a discharge chamber, a plurality of extensions from said enlarged sections into said discharge chamber; and a passage for said gases from said discharge chamber to the atmosphere. 120

9. A muffler for internal combustion engines comprising a relatively enlarged central substantially tubular section into which exhaust gases are adapted to be discharged; a plurality of substantially tubular outer sections disposed around said central section; 125 130

and a plurality of relatively narrow elongated communicating passages disposed to withdraw gases in substantially tangential manner from said central section and to discharge the same in substantially tangential manner into said outer sections.

10. The combination as set forth in claim 9, together with means for cooling said sections and said passages.

11. The combination as set forth in claim 9, together with an enlarged discharge chamber into which the gases from said outer sections are discharged; and means for discharging the gases from said discharge sec-

15 tion to the atmosphere.

12. The combination as set forth in claim 9 together with slotted tubular discharge ex-

tensions for said outer sections; a discharge chamber into which said extensions project; and a passage from said discharge chamber 20 to the atmosphere.

13. The combination as set forth in claim 9, together with a cooling enclosure for said central and outer sections, air inlet and outlet openings in said cooling enclosure; a detachable discharge chamber secured to said cooling enclosure; a removable plate interposed between said discharge and said cooling chamber, and gas outlets for said outer sections extending through said removable plate 25 into said gas chamber.

In testimony whereof, I affix my signature.

ARTHUR H. QUARMBY.
